By Drake & Co. Atty.

UNITED STATES PATENT OFFICE.

GEORGE B. WEBB, OF NEWARK, NEW JERSEY, ASSIGNOR OF ONE-HALF TO
PLUMB & MARCUS, OF SAME PLACE.

ELECTRIC CLOCK.

SPECIFICATION forming part of Letters Patent No. 294,552, dated March 4, 1884.

Application filed September 7, 1883. (No model.)

To all whom it may concern:

Be it known that I, GEORGE B. WEBB, a citizen of the United States, residing at Newark, in the county of Essex and State of New Jersey, have invented certain new and useful Improvements in Electrical Clocks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in clocks, and more especially to those in which the motive power is supplied by electricity, commonly known as "electrical clocks," and is intended to increase the efficiency and regularity thereof by means of such appliances as will be hereinafter described and claimed.

Referring to the accompanying drawings, in which similar letters of reference indicate corresponding parts in each of the figures, Figure 1 is a front elevation of a clock with the dial or face removed, showing the relative position of parts of my invention. Fig. 2 is also a front elevation of the same, the upper half of the front plate being removed, showing the arrangement of the interior works. Fig. 3 is a top view, the escapement rod and wheel being removed to show the parts below. Fig. 4 is a side elevation of the modified form of the upper contact-point. Fig. 5 is a section taken through line *x* of Fig. 1, showing some of the parts; and Fig. 6 is a detailed view of the spring-pawl and auxiliary spring.

In the drawings, *A* is the front plate of the clock. *B* is a lever pivoted thereto at *b*.

b' is the long arm of the lever, provided with an elastic strip, *b'*, which extends under the armature *c*.

b'' is the short arm of the lever, having pivoted thereto the second wheel arbor *b''*, Figs. 3 and 5, to which is attached the lower contact-wheel, *b''*, which moves automatically therewith.

C are the magnets, preferably a pair, secured within a suitable frame attached to the frame-work of the clock.

c is an armature pivoted at *c'* to the frame

of the magnets, and rests upon the magnets, as shown in Figs. 1, 2, and 3. The actuating-arm *D* is screwed or fastened to the armature at one end, the other end carrying the spring-pawl *d*, which engages with the teeth of the actuating-wheel *F*, Fig. 2, said spring-pawl being made of an elastic strip or piece of steel and secured to the actuating-arm *D* by a collar, as shown, or by any suitable device.

d' is a stop on the arm *D*, which moves therewith and with the spring-pawl *d*, and serves to prevent the said spring-pawl from turning the actuating-wheel farther than is required by dropping between the teeth of said wheel.

e is a curved arm that extends under the actuating-wheel and carries the safety-stop *e'*, which, when the action of the spring *O* upon the arm *D* lifts the spring *d* and stop *d'* from their engagement with the actuating-wheel, rises between the teeth of the same and acts as a supplementary stop or catch, preventing any motion of the wheel *E*.

F is the impulse-arm, at one end of which is the elastic strip *f*, by which it is secured to the block *f'*, the other end being threaded to receive a nut, *f''*, to which is attached the accommodating-spring *f''*, as shown in Fig. 1. A collar, *G*, carrying the iridium contact-point *g*, is secured upon the impulse-arm, as shown in same figure. Auxiliary springs *H* and *H'* are employed to stop the vibration of the spring-pawl *d* and accommodating-spring *f''* as they are lifted from their points of engagement with the actuating-wheel and the plate *j'*. The spring *H* is secured to the arm *D* by the same collar that carries the spring-pawl, as shown in Figs. 1 and 2, or in any suitable manner, the other end of said spring bearing against the spring-pawl *d*. The spring *H'* is attached at one end to the nut *f''* upon the impulse-arm, by which the spring *f''* is connected with said arm, and the other end bearing against or just touching said spring *f''* in its normal state of rest, similar to the spring *H*. By using springs *d* and *f''* to impinge upon the actuating-wheel and plate *j'*, the flexibility of said springs prevents their battering or jarring the parts as they engage therewith; and in order to avoid the vibration of said

springs, as mentioned above, the auxiliary springs H and H' are also elastic, so as to vibrate slightly in sympathy with the springs d and f³, and, being a little stronger than said 5 springs, soon stop their vibration. Moreover, the fixed ends of the spring-pawl and auxiliary springs are separated by a small distance, and the free ends of said springs bent to press against or touch the spring-pawl, as 10 shown in Figs. 1 and 2, and in consequence the vibration of the springs causes a slight amount of friction at the point of engagement, which quickly stops the vibration. If said 15 vibration of the springs d and f³ were permitted to continue, the points of contact would vary, and thus seriously impair the operation of the clock.

I is a lever pivoted at i, and having attached at one end a spring, i', which is fastened to the impulse-arm F, and is used to maintain the contact between the upper iridium contact-point, g, and the lower contact-wheel, b⁵. The tension of this spring is regulated by the set-screw i², acting against the short arm of the lever I, as in Fig. 1.

J is the pendulum, swung from the block j, having a projecting arm, j', provided with a set-screw, j², the upper end of which is broadened or provided with a plate, j³, which engages with the spring f³, attached to the impulse-arm, at intervals when the pendulum is in motion.

K in Figs. 1, 3, and 5 is a spring, one end of which bears upon the second wheel arbor b⁴, Figs. 3 and 5, the other end being held in a slit in an insulating-stud, k, said spring serving a double purpose—viz., to preserve the contact on the arbor by its elasticity, and also to automatically lower the end of said arbor and the contact-wheel attached thereto by its pressure.

The course of the electric current and the operation of the various parts of the apparatus are substantially as follows: One wire from 45 the battery enters one of the magnets at l. The other wire is fastened to the spring K, as shown in Figs. 1, 3, and 5. The current passes through the wire at l to one magnet and through the other wire, the spring K, arbor b⁴, and lower contact-wheel, b⁵, thence through the upper iridium contact-point, g, impulse-arm F, spring f, and the wire m to the other magnet, thus 50 completing the circuit. The pendulum is swinging to the right, and the plate j³ strikes and lifts the spring f³, and consequently the impulse-arm F, thus separating the contact-points b⁵ and g and breaking the circuit. The 55 breaking of the circuit frees the armature, which, together with actuating-arm D and the 60 parts attached thereto, is lifted by the retractile spring O. The lifting of the armature releases the spring b² and permits the long arm b' of the lever B to ascend, and the short arm b³ and the contact-wheel b⁵, together with the 65 second wheel arbor, to descend by the pressure of the spring K upon said arbor. This in-

creases the distance between the contact-points, which is determined and regulated by the lug P and the adjustable set-screw p, between which the long arm b' vibrates and occurs 70 while the pendulum is swinging to the right. When the pendulum, in returning, reaches the point where it lifted the spring f³, the said spring f³ still presses upon the pendulum-plate j³, and by the momentum of the pendulum and 75 the force of the spring i', acting through the impulse-arm, transmits enough power to send the pendulum to the left before the contact-point on the impulse-arm completes the circuit by touching the lower contact-wheel, (because of the increased distance.) The increased distance between the contact-points enlarges the arc of vibration of the impulse-arm, said enlargement constituting the arc of 80 impulse which carries the pendulum over the center of gravity and keeps it oscillating. The pendulum, on its return from the left, again engages with the spring f³, and the same operation is repeated. The moment the contact-points touch the current is re-established, and 85 the magnets attract the armature, which thereby lowers the actuating-arm D and the spring-pawl d, which engages with the teeth of the actuating-wheel and turns it. The armature, when attracted by the magnets, presses upon 90 the spring b², thus lowering the long arm of the lever B, and raising the short arm that carries the contact-wheel b⁵ and the arbor b⁴ to their primary position, also lifting the impulse-arm therewith.

The upper contact-point is made, preferably, of iridium, suitably secured to the impulse-arm. A collar, as G, may be employed. The lower contact-wheel, b⁵, is made of any suitable material, as brass, and is provided with 95 a rim, b⁶, of platinum or other non-oxidizing metal. Instead of the metals named, others may be used which possess the requisite properties of hardness, &c.

As the contact-wheel b⁵ turns once in about 100 eight minutes with the second wheel arbor b⁴, every point of its continuous peripheral surface, said peripheral surface being made entirely of conducting material, is worn equally by the contact of the points. In order to reduce the wear and friction upon the same, I may use, instead of the iridium point g, Fig. 1, a wheel, g', similar to the lower contact-wheel, working on an arbor in the end of the impulse-arm or attached thereto in any suitable manner, as shown in Fig. 4. A spring, g², or flexible shaft is attached to said wheel g' or to the axle thereof by one end, and by the other to one of the clock-arbors, as the third wheel arbor and revolving therewith, thereby 115 securing an automatic and a slow and regular rotary motion in the wheel g'. By this construction the contact-wheels are rotated independently.

The pendulum-rod J may be made of a brass outer tube, R, zinc middle tube, S, and central steel rod, T, as shown in Fig. 1, thereby pro-

ducing a compensating pendulum that is sufficient and economical. The pressure of the spring K upon the arbor b^4 should be just enough to depress the contact-wheel b^5 and the short arm b^6 of the lever when required, and yet permit said arbor to revolve, the arbor and wheel thus having at the same time at intervals a double motion—one a rotary motion, and the other dependent upon the action of the lever B upward and downward—as will be readily understood.

The moment the current is re-established by the contact of the points the wheels of the clock begin to move, as herein described. This motion is communicated to the contact-wheel b^5 , the surface of which in turning scrapes against the point g , thus removing the deposits resulting from combustion and oxidation, which would accumulate upon the wheel when made entirely of brass or any ordinary metal, and which would, if permitted to collect in one place, tend to insulate the points and break the circuit.

The points of attachment of the spring i' to the impulse-arm F and the upper surface of the plate j^3 are insulated, as also the point of attachment of the impulse-arm to the front plate.

The batteries may be placed in any convenient location.

Having thus described my invention, what I claim is—

1. In an electric clock, the combination, with an escape-wheel and an actuating-arm of a clock, of a spring click or pawl secured upon said arm, adapted to engage with said wheel, and an auxiliary spring also secured to said arm and bearing against said spring-click to prevent the vibration thereof, substantially as set forth.

2. In combination, a spring-pawl, d , an auxiliary spring, H, a clock-wheel, and a stop, d' , all as set forth.

3. In a clock, the combination of a spring-pawl, d , a toothed wheel, E, a stop, d' , and a safety-stop (as e') adapted to engage with the teeth of the wheel when the spring-pawl is disengaged from said wheel, all substantially as set forth.

4. In combination, a spring-pawl, d , a toothed wheel, E, a stop, d' , a safety-stop, e' , and means whereby said stop e' and spring-pawl d may be operated simultaneously, all substantially as set forth.

5. A clock-arbor (as b^4) having attached thereto a contact-wheel, (as b^5), both of which have a rotary motion, and at the same time at intervals an upward and downward motion, all substantially as and for the purposes set forth.

6. In an electrical clock, the combination of a lever, (as B,) contact-wheel, (as b^5), spring-piece b^2 , and means for regulating the extent of vibration of said lever, all as set forth.

7. In combination, an impulse-arm, F, adapted to carry a contact-point, a spring, f^3 ,

auxiliary spring H', a pendulum, J, provided with an arm, j' , and means for depressing said impulse-arm, all substantially as and for the purposes set forth.

8. The combination, with the pendulum of a clock, of a spring, i' , impulse-arm F, accommodating-spring f^3 , and means for regulating the tension of the spring i' , (as I,) all as set forth.

9. In combination, the magnets C, armature c , actuating-arm D, means for raising said arm, (as the spring O,) a spring-pawl, d , secured to said actuating-arm, and adapted to engage with a toothed wheel, an auxiliary spring, H, and a stop, d' , both of which are also secured to said actuating-arm, all as set forth.

10. A clock-arbor having attached thereto a contact-wheel provided with a continuous peripheral surface of conducting material.

11. The combination, with a clock-arbor, b^4 , having secured thereto a contact-point, of mechanism whereby said arbor and contact-point may be raised and lowered, all as set forth.

12. In an electrical clock, the combination of co-operating contact-wheels, and mechanism whereby both of said wheels may be rotated automatically and independently, all substantially as and for the purposes set forth.

13. In combination, a clock-arbor, a contact-point, a spring, K, and means for raising said contact-point and arbor, all substantially as and for the purposes set forth.

14. In combination, a clock-arbor, a contact-point, a spring, (as K,) and a lever, (as B,) a magnet, C, armature c , and means for regulating the extent of the movement of said lever, all substantially as and for the purposes set forth.

15. In combination, a lever, B, contact-wheel b^5 , arbor b^4 , spring K, impulse-arm F, contact-point g , and means for lowering said arm, all substantially as set forth.

16. In a clock, the combination of a pawl, a toothed wheel, E, a stop, d' , and a safety-stop (as e') adapted to engage with the teeth of said wheel when the pawl and stop d' are disengaged therefrom, substantially as set forth.

17. In combination, an impulse-arm, automatically-rotating contact-wheels, one of said wheels being attached to a clock-arbor, the other to said impulse-arm, and a pendulum, substantially as set forth.

18. In combination, a pendulum, an automatically-rotating contact-wheel, an impulse-arm, and a contact-point attached to said impulse-arm, substantially as described.

In testimony that I claim the foregoing I have hereunto set my hand this 31st day of August, 1883.

GEORGE B. WEBB.
